CLAIM

We claim, the ornamental design for a reaching tool, as shown and described.

DESCRIPTION

FIG. 1 is a perspective view of reaching tool, showing our new design;

FIG. 2 is another perspective view thereof;

FIG. 3 is a side elevation view thereof;

FIG. 4 is another side elevation view thereof;

FIG. 5 is a top plan view thereof;

FIG. 6 is a bottom plan view thereof;

FIG. 7 is a front elevation view thereof; and,

FIG. 8 is a rear elevation view thereof.

The broken-line disclosure depicts portions of the reaching tool in which the design is embodied that are not considered part of the claimed design.

1 Claim, 5 Drawing Sheets
